BOTTLE

Philip Allan Hodge, Warwick, R.I., assignor to Anson, Inc., Providence, R.I., a corporation of Rhode Island

Filed Aug. 26, 1966, Ser. No. 3,598

Term of patent 14 years

Int. Cl. D9—01

U.S. Cl. D9—54

FIG 1

FIG 5

FIG 3

FIG 2

I claim:

The ornamental design for a bottle, as shown.
